(57) **CLAIM**

The ornamental design for a lighting fixture, as shown and described.

DESCRIPTION

FIG. 1 is a perspective view, from the bottom, of a first embodiment of a lighting fixture in accordance with the new design;

FIG. 2 is a front view thereof, with the rear view being a mirror image;

FIG. 3 is a left side view thereof;

FIG. 4 is a right side view thereof; and

FIG. 5 is a bottom view thereof, with the top forming no part of the claimed design;

FIG. 6 is a perspective view, from the bottom, of a second embodiment of a lighting fixture in accordance with the new design;

FIG. 7 is a front view thereof, wherein the rear view is a mirror image;

FIG. 8 is a left side view thereof, wherein the right side view is a mirror image;

FIG. 9 is a bottom view thereof, with the top forming no part of the claimed design.

FIG. 10 is a perspective view, from the bottom, of a third embodiment of a lighting fixture in accordance with the new design;

FIG. 11 is a front view thereof, with the rear view being a mirror image;

FIG. 12 is a left side view thereof;

FIG. 13 is a right side view thereof;

FIG. 14 is a bottom view thereof, with the top forming no part of the claimed design;

FIG. 15 is a perspective view, from the bottom, of a fourth embodiment of a lighting fixture in accordance with the new design;

FIG. 16 is a front view thereof, wherein the rear view is a mirror image;

FIG. 17 is a left side view thereof, wherein the right side view is a mirror image; and,

(Continued)

FIG. 18 is a bottom view thereof, with the top forming no part of the claimed design.

The broken lines in the drawings illustrate portions of the lighting fixture which form no part of the claimed design.
